UNITED STATES PATENT OFFICE.

DAVID T. OWEN, OF CLEVELAND, OHIO, ASSIGNOR TO THE D. T. OWEN COMPANY, OF CLEVELAND, OHIO, A CORPORATION OF NEW JERSEY.

FOLDING BED.

SPECIFICATION forming part of Letters Patent No. 791,717, dated June 6, 1905.

Application filed September 12, 1903. Serial No. 172,855.

To all whom it may concern:

Be it known that I, DAVID T. OWEN, a citizen of the United States, residing at Cleveland, in the county of Cuyahoga and State of Ohio, 5 have invented certain new and useful Improvements in Folding Beds; and I do declare that the following is a full, clear, and exact description of the invention, which will enable others skilled in the art to which it appertains 10 to make and use the same.

My invention relates to folding beds, and is an improvement in that class of beds having head and foot sections adapted to fold down upon the bedclothing when the bed is raised 15 and placed out of use; and the improvement consists in the arrangement and construction of parts, substantially as hereinafter shown and described, and more particularly pointed out in the claims.

20 One of the objects of the invention is to provide simple and effective means to automatically raise and lower the head and foot sections when the bed is operated and which will hold said end sections securely when thus 25 raised and lowered.

Another object is embodied in the means for supporting the bed at its front when lowered, and which means is automatically operative and dependent upon the movement of the end 30 sections.

Another object is embodied in the arrangement and construction of the bed pivot and support whereby the bed is adapted to rest at one side of its pivoted center when in upper 35 right position and which when the bed is lowered brings the bed to the required elevation for use.

Another object is to produce a folding bed combined with a couch and wherein the bed is 40 supported in part by the couch; and a further object is to provide a separable and knock-down structure which serves as a couch-frame and an inclosing casing for the bed.

In the accompanying drawings, Figure 1 is 45 a cross-sectional view of my combined couch and folding bed with the parts in position as in use as a couch and showing the bed in dotted lines as partly lowered and at the angle when the links act to raise the bed end sections.

Fig. 2 is a similar cross-section to Fig. 1, but 50 with the bed down and showing the end section raised and the supporting-leg at the front down. Fig. 3 is an end elevation of a front corner-post of the bed-frame. Fig. 4 is an elevation looking at the front of the bed-frame 55 and showing the leg and end-section connections as they appear when the bed is lowered; and Fig. 5 is a similar view, but showing the leg and end sections folded upon the bed-frame, as occurs when the bed is raised. Fig. 60 6 is a rear elevation of part of the bed and couch and showing the bed and an end section and the means for operating the section as when the bed is lowered; and Fig. 7 is a similar view, but showing the parts as they appear 65 when the bed is raised and confined within the inclosing casing.

The bed in this instance is shown as connected and related to a couch, and the bed-bottom is finished or upholstered to form the 70 back of the couch; but my improvement is not necessarily limited to the form or style shown; but, as shown and hereinafter fully described, the bed and couch have new and novel features of construction, which when 75 combined serve to support and also to frame in the bed and whereby a separable and knock-down structure is obtained to facilitate handling and shipping. Thus A represents a bed or

bed-frame provided with a suitable spring-bottom 2, and B a couch or couch-frame having a spring upholstered seat 3. An inclosing casing C is detachably connected with couch-frame B by means of a slotted plate 4, fastened to each side or end of the couch-frame, and which plate is engaged by pins or headed rivets 5 on the inside face of said casing at its bottom. Casing C serves as a finishing-border for the couch when the bed is raised and conceals the bed from view except 90 at its bottom, which is upholstered or finished to harmonize with the upholstering or finish of couch B. Bed-bottom upholstering or finish 6 is preferably a separate and removable part of bed A and is herein shown as attached 95 at one edge to a swinging door or hinged cross-bar 7, mounted upon the bottom of the bed-frame at its front; but this front appears as

the top when the bed is raised and as seen in Fig. 1. The opposite edge or side of upholstering or finish 6 is connected with the rear portion of bed-frame A by means of a series 5 of coiled springs 8, which keeps said upholstering taut and flush against the bed spring-bottom 2 when the bed is raised and in use as the back of couch B. A suitable catch or dog 9, mounted upon door or bar 7, engages top 10 board 10 of casing C and locks said plate or bar against outward movement until released by button 11.

Bed-frame A is preferably of tubular construction and provided with corner-castings 15 12 and 12', respectively. The rear corner-castings 12 have an L-shaped extension or leg-support 13, which is detachably and pivotally connected, by means of bolt 14, with a supporting plate or casting 15, mounted upon 20 plate 4 of couch-frame B. Extension 13 is preferably constructed in the L form, as shown, to provide and locate a pivot for the bed somewhat forward of the bed proper when in upright position, so that the bed will rest by 25 its own weight safely and securely within casing C, and thus overcome the slightest tendency of the bed to tipping or folding down when the couch is in use. It is also desirable to have the bed when in casing C rest 30 down as low as possible to obtain stability to the whole structure and also to decrease the height of casing C to bring it into pleasing proportions with the couch, and as it is also necessary to bring the bed to a certain elevation and plane above couch B to be out of 35 contact therewith when the bed is lowered and when in use as a bed the L-shaped extension as described has been found to meet all these requirements. Then, again, with the 40 pivot located as shown and with the construction as described the bed is carried entirely out of the casing and without in any wise disturbing or engaging the couch-seat or upholstering.

45 The end sections D of bed A are pivotally supported at *d* upon corner-castings 12 12' at one side of the axial center of said sections and the rigid post 17 of said castings, and said sections when raised rest and engage upon 50 the top of said posts. The means for operating sections D comprises a single rigid rod or link 18, Figs. 2 and 6, which connects with a crank-arm 19 on pivot member 20 of each section D and engages and is held and confined at its opposite end in a slotted keeper 21, which forms part of pivot-support casting 15 55 on couch-frame B, although said keeper may in some instances be a separate part and independently supported. The end of rod or link 18 is bent at right angles and is upset or provided with a head or enlargement at its end to confine it within keeper 21. The slot of said keeper is enlarged at one end to permit the head or enlarged end of rod 18 to pass 60 through when said parts are to be connected

or taken apart. In operation it is desirable that the end sections should not respond or move immediately upon the initial lowering of the bed, because in some instances where the end sections are exceptionally high or of some peculiar shape or design said ends are apt to strike the wall if the couch be placed or backed against a wall. Keeper 21 is therefore slotted to permit link or rod 18 to slide within limits, and the end sections do not begin to rise until said link comes to the outer end of the keeper-slot. The lowering of the bed from upright position raises the bed at the rear and draws the link back to its limit of movement in the slot, when it then 70 begins to pull arm 19 to raise the end sections until they are seated upon posts 17 and where they are securely held in place by link 18 until the bed is raised. When bed A is raised, link 18 pushes or lifts end sections D off their 75 seat and all during a short arc travel of the link with the right-angled end at the end of the slot in keeper 21 as the fulcrum of this movement and until the said sections are sufficiently tilted on their pivots to shift the center of gravity of said sections, and thereafter their own weight will carry them down upon the bed; but their fall is still regulated and controlled by link 18 and the movement of the bed. Then when said ends are fully down 80 and upon the bedclothes link 18 is forced back in the slot of keeper 21 until the bed rests within casing C.

85 A coiled spring 22 is shown as connected to link 18 for reasons hereinafter stated; but as a matter of fact said link is compelled and will act without the aid of a spring; but in some cases it may be desirable to utilize the spring to bring the link always to its limit and also to provide a spring tension upon the 90 end sections, so that they will bear yieldingly upon the bedclothing when the bed is raised and the sections are down.

95 In the event that lower or specially-designed 100 head and foot sections are used or if the casing or couch is modified or wherever there is no objection to raising the ends immediately upon the initial lowering of the bed link 18 may have merely a fixed pivotal connection at its lower end and need not have a sliding engagement within a keeper, as shown.

105 When the bed A is lowered, the raising of the end sections by the means described also 110 brings the front legs 25 of the bed into their proper place to support the bed at its front, and to all intents and purposes said leg then 115 appears as a continuation and part of the end section-rail. Both leg 25 and section D have a pivot member 26 and 27, respectively, which is pivotally mounted upon casting 12' at one 120 side of the axial center of leg 25 and section D, as seen in Fig. 4, and said members are 125 provided with intermeshing teeth which carry the movement of section D forward to leg 25. When unfolded, as seen in Fig. 4, shoulder 130

28 of member 26 bears against the bottom of lug or post 17 on casting 12', and the weight of the bed at the front is mainly carried by said lug or post resting upon the top 5 or shoulder of the leg. With the pivot at one side, as described, the weight of the bed and all the weight carried thereby always tend to more securely lock the leg in place, and as the main strain is directly downward 10 a rigid and safe support for the bed is assured. When the bed is raised to vertical position, legs 25 are folded in, as seen in Fig. 5, and lie parallel with and at one side of the tubular front rail of bed-frame A. Cross-bar or door 15 7 is pivoted or hinged upon lug 30 of casting 12' and when unlatched swings back out of the way of legs 25 and permits them to pass. When bed A is down, the upholstering 6 drops down with door or plate 7 and away 20 from bed spring-bottom 2.

The posts 17 of castings 12' of bed A when within casing C engage and rest against blocks 31 and limit the backward movement of the bed. End sections D are prevented from unfolding by said blocks as well because of their engagement at 32, Fig. 7.

To separate the bed, couch, and casing merely requires the lifting of casing C to release pins 5 from the slots of plate 4 and the 30 removal of pivot-bolts 14 and disconnection of link 18 from its keeper.

What I claim is—

1. In folding beds, a supporting-frame and a bed-frame pivoted thereon, end sections 35 pivoted upon said bed-frame and adapted to fold at right angles to the folding of said bed-frame, and a link providing a direct connection between said supporting-frame and each end section whereby said sections are folded 40 and unfolded when the bed is raised and lowered, substantially as described.

2. A folding bed and a support therefor and end sections adapted to fold upon the bed, a crank-arm integral with each section at the 45 rear side of said bed and projecting inward toward the opposite end section, and a single link pivotally connecting said crank-arm and said support whereby said sections are raised and lowered when the bed is unfolded and 50 folded, substantially as described.

3. A folding bed and a support therefor and folding end sections for said bed, and a single link for each section having a sliding connection with said support adapted to raise said 55 sections on an arc of substantially ninety degrees during a less arc movement of said bed, substantially as described.

4. A folding bed and a support therefor, folding end sections mounted on said bed, slotted keepers mounted upon said support, and a rigid link directly connecting each section 60 with a slotted keeper and having sliding engagement with the latter to control the folding of said sections when said bed is folded, 65 substantially as described.

5. A support and a bed pivotally mounted thereon and folding end sections for said bed, a single link connected with each section, a keeper for the link mounted upon said support and a spring attached to said link and 70 said support to hold said links and sections under spring tension when said sections are folded, substantially as described.

6. A base and a bed pivoted thereon, folding end sections for said bed having pivots at 75 one side of the axial center of said sections, a crank-arm integral with each section at the rear side of said bed and projecting inward toward the opposite end section, and a link pivotally connected with said crank-arm and 80 base at the rear side of said bed and whereby direct actuation is imparted to each section when the bed is folded and unfolded, substantially as described.

7. A supporting-base and a bed pivoted 85 thereon and folding end sections pivotally mounted on said bed, a keeper mounted on said base and a slot in said keeper, and a single link connected between each end section and said keeper and free to slide within limits in 90 said slot and whereby said sections are raised when said link reaches the end of said slot as the bed is lowered, substantially as described.

8. A folding bed and folding end sections mounted on said bed, a pivot member for the 95 bed and a slotted keeper integral with said member, and a single link between each end section and keeper whereby a direct rigid actuating connection is maintained to lower said ends when the bed is folded and unfolded, 100 substantially as described.

9. A folding bed and folding legs at the front corners of said bed, folding sections at each end of said bed, operating connections between each end section and its companion 105 leg for providing joint folding and unfolding, a support for the bed, and a single link connecting each end section at the rear side of the bed with said support whereby folding and unfolding of said sections and legs are provided for when said bed is raised and lowered, 110 substantially as described.

10. In a folding bed, a bed-frame and a folding section mounted upon said frame at each end, a support for said frame at the rear of 115 said bed, a single independent rigid connection between each folding section and said support, independent legs at the front and ends of said frame, and folding connections between each end section and each leg, substantially as 120 described.

11. A folding bed and folding end sections thereon, folding legs at the front of said bed, said sections and legs each having pivot members provided with intermeshing gear-teeth, 125 and a link connection to fold said sections when the bed is folded, substantially as described.

12. A folding bed having a pivot-support at its rear, end sections pivotally mounted on said 130

bed, a single rigid link connection between said support and end sections to fold the sections when the bed is folded, folding legs pivotally mounted on said bed at its front, and 5 intermeshing gear-teeth between said sections and said legs to fold the legs when the sections are folded, substantially as described.

13. The combination of a folding bed with a couch, an upright inclosing casing for the bed, 10 folding legs mounted upon the front of the bed, a door hinged across the front of the bed, a finished back for the couch stretched across the bottom of said bed and separate therefrom and having one edge attached to said 15 door, substantially as described.

14. The combination of a couch with a bed pivotally mounted thereon, folding legs at the front of said bed, a couch-frame having an upright inclosing casing for the bed, a hinged 20 door mounted upon the front of said bed, a finished back for the couch separably stretched over the bottom of the bed, said back having

25 springs connecting one edge thereof with the bed and the opposite edge attached to said door, substantially as described.

15. In a folding bed, a bed-frame, and a rigid supporting-leg at the rear and corners of said frame comprising a right-angled arm having one portion extending at right angles to the plane of the bottom and an outer portion 30 thereof extending inward therefrom on a parallel plane with and below the line of the bottom of said bed-frame, a pivot connection and support for said leg at the end of said outer portion, and means to support the front side 35 of the bed-frame when lowered, in combination with a couch-seat.

In testimony whereof I sign this specification in the presence of two witnesses.

DAVID T. OWEN.
